UNITED STATES PATENT OFFICE.

JOHN DESMOND, OF CHICAGO, ILLINOIS.

PUMP.

No. 882,874.

Specification of Letters Patent. Patented March 24, 1908.

Application filed February 12, 1906. Serial No. 300,599.

To all whom it may concern:

Be it known that I, JOHN DESMOND, a citizen of the United States, residing at Chicago, in the county of Cook and State of Illinois, have invented certain new and useful Improvements in Pumps, of which the following is a specification.

My invention relates to improvements in pumps, and more especially to vacuum air pumps.

One of the objects of my invention is to provide a packing upon the suction end of the pump barrel, adapted to afford a tight seat against a smooth flat surface and to permit considerable lateral movement of the free end of the pump without disturbing or injuriously affecting the air tight seat thus established.

Another object of my invention is to provide a resilient, expanding, substantially annular ring or the like, placed under tension within the cup-packing of the plunger-piston to yieldingly hold the lateral walls thereof against the side walls of the pump barrel or cylinder. And a still further object of my invention is to provide a loose annulus, consisting of lubricating material or a carrier for such material loosely arranged around the piston rod, and adapted by virtue of eccentric positions, which it may assume, to be brought from time to time into contact with various parts of the side walls of the pump barrel, or cylinder, whereby said walls and the packing-cup of the plunger or piston may be thereby readily maintained in a lubricated condition.

In the drawings, Figure 1 is a sectional elevation of the pump; Fig. 2 is an enlarged section of a fragment of the pump barrel, the piston rod and piston. Fig. 3 is a cross section taken on line 3—3 of Fig. 1. Fig. 4 is a similar view taken on line 4—4 of Fig. 1.

In all of the views the same numerals of reference indicate similar parts.

The barrel or cylinder is indicated by 5, and 6 is the piston rod. The piston in general is indicated by 7. The packing-cup 8 of leather or similar material, is held in position on the piston rod 6 by the usual means of washers 9 and 10, and the nut 6^a, the side wall 11 of which is evenly pressed against the walls of the cylinder 5 by means of the resilient expanding ring 12, which is placed within the packing-cup 8 and which, being under tension, exerts an outwardly directed pressure to maintain said side wall 11 of the cup

8 in yielding intimate contact with the interior surface of the pump-barrel or cylinder 5, thereby providing an air tight contact between the piston and said cylinder.

An annulus 13 may be made of lubricating material, such as plumbago and tallow pressed into shape with sufficient pressure to render it hard and compact so that it will maintain its form for a long period of time, or it may contain other materials or binders such as paraffine, which will raise its temperature coefficient or melting point, and thereby increase its durability and at the same time not impair its lubricating qualities. Or the ring or annulus 13 may be a carrier for a lubricator, such as felt or the like, having its pores filled with a lubricating agent, such as plumbago and tallow or the like, forced into the carrier while hot.

The annulus should contain a central opening much larger in diameter than the rod it surrounds so that it may occupy various eccentric positions, with reference to the rod, on all sides and thereby make contact with the respective sides of the interior surface of the pump cylinder. The lubricating material, thus imparted to the cylinder, will be partially absorbed by the leather cup 8 and thus the cup will retain its necessarily flexible condition for long periods of time without the necessity for its special and periodical application.

The lower end of the pump cylinder is outwardly flanged, as at 14, over which a tapered, soft rubber ring or annulus 15 is expanded, the latter being held in place by means of an overlying, correspondingly tapered metal ring 16, having its smaller end soldered, brazed or otherwise secured to the body of the pump cylinder, an air tight joint between the ring and the pump cylinder being thus provided.

The rubber ring 15 descending below the more rigid portions of the structure permits a considerable latitude of lateral movement of the free end of the pump without decreasing the contact of the lower surface of the ring 15 with the smooth flat surface upon which the pump may be placed prior to its operation.

When pumps of the character described are to be used for household purposes, such as in hermetically sealing jars of fruit, condiments, etc., by extracting most of the air and gases therefrom, the construction herein set forth is especially desirable. For such

use some means must be provided for automatically supplying the lubricant and for preventing the drying and shrinking of the cup-packing, and for permitting the use of 5 such pump without requiring too great precision in its application and operation.

While I have described a single embodiment of my invention I do not desire to be understood as limiting my invention to the 10 specific construction disclosed, as considerable latitude of variation may be made from that set forth without departing from the spirit and scope of my invention.

Having thus described my invention, what 15 I claim and desire to secure by Letters Patent, of the United States, is:

1. In a pump the combination of a piston, a piston rod for moving said piston, and an 20 annular lubricating medium loosely encompassing the piston rod.
2. In a pump the combination of a piston,

a piston rod for moving said piston, a pump barrel and an annular lubricating medium in said barrel, loosely encompassing the piston rod and overlying said piston.

25

3. In a pump, a cylinder closed at one end around the piston rod, and at its other end open, the cylinder being of uniform diameter to a point adjacent its open end and at said open end outwardly flared, a piston in the cylinder, the piston rod, a ring of rubber of flaring shape having its smaller end overlying the flaring end of the cylinder, and at its expanded end free and projecting beyond the cylinder, and means for securing 30 said ring upon the cylinder.

In testimony whereof I hereunto set my hand in the presence of two witnesses.

JOHN DESMOND.
